CLAIM

The ornamental design for a vacuum hose as shown and described.

DESCRIPTION

FIG. 1 is a front, top perspective view of a vacuum hose, showing my new design;

FIG. 2 is a rear, bottom perspective view thereof;

FIG. 3 is a front elevational view of the reduced scale thereof, the rear elevational view being a mirror image of FIG. 3;

FIG. 4 is a left side view of the reduced scale thereof;

FIG. 5 is a right side view of the reduced scale thereof;

FIG. 6 is a top plan view of the enlarged scale thereof;

FIG. 7 is a bottom plan view of the enlarged scale thereof;

FIG. 8 is a partial enlarged view of FIG. 1;

FIG. 9 is a partial enlarged view of FIG. 4; and,

FIG. 10 is a partial enlarged view of FIG. 6.

The dashed broken lines in the figures are for the purposes of illustration portions of the vacuum hose, which form no part of the claimed design.

The dash-dot lines illustrate the boundary of the enlarged views and form no part of the claimed design.
